UNITED STATES PATENT OFFICE.

CHARLES C. WHITE, OF CHICAGO, ILLINOIS.

BUILT-IN CHINA CLOSET.

Application filed December 19, 1921. Serial No. 523,358.

To all whom it may concern:

Be it known that I, CHARLES C. WHITE, a citizen of the United States, and a resident of Chicago, in the county of Cook and State 5 of Illinois, have invented certain new and useful Improvements in Built-In China Closets, of which the following is a full, clear, and exact description.

The invention relates to built-in china 10 closets and its object is to provide an improved closet which is adapted to be built into a room and which is more particularly adapted for use in kitchenette apartments. The object of the invention is to provide a 15 china closet of improved construction.

In the drawings: Fig. 1 is a section through a pair of china closets embodying the invention. Fig. 2 is a side elevation of one of the closets and Fig. 3 is a section of 20 the other closet. Fig. 4 is a vertical section on line 3—3 of Fig. 2.

The invention is exemplified in a pair of closets A and B which are usually installed in a connecting passageway between the 25 living and dining room and the kitchen in kitchenette apartments, a space being left between them to serve as a passageway between the rooms. These closets are similar in structure, so that a description of one will 30 suffice for both. Each has one of its ends unfinished and adapted to fit against one of the room walls C.

Each closet comprises a unit composed of a base 7, sides 8, a top 9, an unfinished end 35 10 adapted to fit against one of the walls C and an outer end 11 all rigidly secured together and assembled at the factory. One side is provided with a veneer panel 12 and the other side is provided with a hinged 40 door 13 which is provided with a window 14. A panel 15 is provided in the exposed end 11. A base-board 16, conforming to the base-board of the room is placed around the sides and exposed end of the unit to finish the 45 lower end of the cabinet and give it the appearance of a built-in unit. A characteristic of this construction is that the unit may be assembled at the factory, and the base-board 16, corresponding to the base- 50 board of the room, is fitted around the base-

portion of the cabinet, so that the minimum amount of work will be involved in installing the closet.

In kitchenette apartments, it is frequently difficult or impossible to provide a convenient place for the table linen and silverware and one object of the invention is to provide a convenient place for keeping such articles where they will not be exposed but convenient of access. Each closet is provided 55 with shelves 17 to support dishes and the upper shelf 18 is disposed near the top 9 so as to form a shallow compartment 20. The shelf 18 is disposed above the upper margins of door 13, so that the compartment 60 20 will be concealed. A tray 23 for silverware or a tray 24 adapted to hold table linen fit into either one of the compartments 20 of the units respectively. When the door 13 is open, the tray may be removed from the 65 compartment 20 and when closed, the top rail 21 will close the open side of compartment 20.

The invention exemplifies a china closet 70 which may be advantageously installed and 75 is particularly adapted for use in kitchenette apartments.

The invention is not to be understood as restricted to the details set forth, since these may be modified within the scope of the 80 appended claims, without departing from the spirit and scope of the invention.

Having thus described the invention, what I claim as new and desire to secure by Letters Patent, is:

The combination with a built-in wall having a base-board, of a china closet consisting of a factory-built unit having relatively narrow ends and wide sides and a closed top, one of the ends being unfinished and fitting 85 against said wall, and the other finished, the sides being finished and one of them having a door with a window therein, and a base-board extending around the finished ends and sides, forming a continuation of the 90 base-board of the wall, the closet forming, when secured against the wall, a built-in structure.

CHARLES C. WHITE.
